United States Patent Office

Des. 211,641
Patented July 9, 1968

211,641

ELECTRIC LAMP AND THE LIKE

Joseph H. Schlessel, Great Neck, N.Y., assignor, by mesne assignments, to Airequip Inc., New Rochelle, N.Y., a corporation of New York

Filed Jan. 23, 1967, Ser. No. 5,520

Term of patent 14 years

(Cl. D26—8)

FIG. 1 is a perspective view of an electric lamp and the like, showing my new design;

FIG. 2 is a side elevational view thereof;

FIG. 3 is a front elevational view thereof; and

FIG. 4 is a top plan view thereof.

The dominant features of my design reside in the portions shown in full lines.

I claim:

The ornamental design for an electric lamp and the like, substantially as shown and described.
